ASH TRAY

Earle W. Clark, Ada, Mich., assignor to Erinco Products,
Grand Rapids, Mich., a corporation of Michigan

Filed Oct. 12, 1960, Ser. No. 62,451

Term of patent 14 years

(Cl. D85—2)

FIG. 1

FIG. 2

FIG. 4

FIG. 1 is a front perspective view taken from one side of an ash tray showing my new design;

FIG. 2 is a top plan view thereof;

FIG. 3 is a front elevation of the ash tray of FIG. 2; and

FIG. 4 is a vertical section along line IV—IV of FIG. 2.

I claim:

The ornamental design for an ash tray, substantially as shown.
